United States Patent Office.

SPENCER H. BROWN AND CHARLES H. WILLETS, OF NEW YORK, N

Design No. 3,362, dated February 9, 1869.

DESIGN FOR A BUSTLE.

The Schedule referred to in these Letters Patent and making part of the same.

To all whom it may concern:

Be it known that we, SPENCER H. BROWN and CHARLES H. WILLETS, both of the city, county, and State of New York, have invented a new and original Design for Bustles; and we do hereby declare the following to be a full, clear, and exact description thereof, which will enable those skilled in the art to make and use the same, reference being had to the accompanying drawing, forming part of this specification, which drawing, consisting of only one figure, represents our new and original design for bustles.

The drawing represents our design applied to an air-bustle.

The inner circumference is an unbroken or continuous curved line, but the outer circumference has two

curves, whose ends, at the back of the bustle, are separated by a projecting point.

The outer circumference has a fringe, that extends from one end to the other of the bustle.

Having thus described our invention, What we claim as new, and desire to secure by Letters Patent, is—

The above-described design for bustles.

This specification signed by us, this 25th day of January, 1869.

SPENCER H. BROWN
CHAS. H. WILLETS.
